(57) CLAIM

The ornamental design for a shoe, as shown and described.

DESCRIPTION

This application is related to co-pending application Ser. No. 29/461,150 filed Jul. 18, 2013 and titled “Shoe”.

FIG. 1 is a side view of a shoe, showing my new design.

FIG. 2 is a top view thereof; and,

FIG. 3 is a back view thereof.

The longer broken lines on the shoe sole, logo, and the word “ELEFANT” of FIGS. 1-3 are included to show unclaimed subject matter only and form no part of the claimed design. The smaller broken lines on the shoe upper, tongue, and heel of FIGS. 1-3 are included to show unclaimed stitching on the article.
